3,169,811 STORE FIXTURE

Robert J. Stewart, Sparta, Mich., assignor to The Bulman Corporation, Grand Rapids, Mich., a corporation of Michigan

Filed June 28, 1961, Ser. No. 120,283
6 Claims. (Cl. 312—140.1)

This invention relates to store counters and particularly to the type thereof which can be readily manufactured and shipped in a knocked-down condition and which can be readily assembled to provide a variety of specific arrangements.

In the designing of counters and cabinets for retail establishments of various types, it has long been recognized that different specific shapes and styles of counters and cabinets are required for different types of stores and/or for different locations and uses in a given store. This presents many problems. First, for a given manufacturer to provide a complete line of counters and cabinets, each adapted for only one use, would be prohibitively costly. Hence, for manufacturing and inventory purposes it is desirable that a single article of manufacture be adaptable to a wide variety of specific uses. Second, since the requirements within a given store will change from time to time, it is equally necessary that a merchant be able to modify a given counter assembly through a wide variety of specific arrangements so that such counter can be used in a variety of locations within his store and for a variety of different uses.

However, it is also desirable that such counter and cabinet assemblies be shipped from the point of manufacture thereof to the point of use in a knocked-down condition and then assembled at the point of use, usually by the purchaser. Since the purchaser or his employees usually are not experienced in the construction and assembly of counters and cabinets, it is essential that the assembly thereof be very simple and, preferably, be such that it be substantially self-evident with little, if any, need for referring to directions or charts.

A large number of counters and cabinets have previously been offered to the trade in order to meet the above outlined requirements and some of them have been well accepted and are in regular commercial use. However, in a continuing effort to improve on the devices provided to meet the needs above outlined, the herein illustrated and described invention has been brought forth.

Accordingly, the objects of the invention include the following:

(1) To provide a store counter construction which can be shipped in knocked-down form and which can be readily assembled by the purchaser at the site of use.

(2) To provide a store counter construction, as aforesaid, which can be readily modified to provide a variety of different arrangements.

(3) To provide a store counter construction, as aforesaid, wherein a variety of modifications in a basic unit may be made either by the manufacturer prior to shipment or by the purchaser at the site of use and in either case can be made with only a relatively small number of additional parts.

(4) To provide a store counter construction, as aforesaid, which will be of sufficiently simple construction that it can be manufactured economically and can be assembled easily.

(5) To provide a store counter construction, as aforesaid, in which the assembly thereof can be carried out by relatively unskilled persons and by the use of only simple tools.

(6) To provide a store counter construction, as aforesaid, which will be sufficiently sturdy that it can withstand rigorous use for a long period of time.

2

(7) To provide a store counter construction, as aforesaid, wherein the several parts are readily separable from each other so that in the event of damage to a given part it can be easily and quickly replaced.

5 Other objects and purposes of the invention will be apparent to persons acquainted with apparatus of this general sort upon reading the following disclosure and inspecting the accompanying drawings.

In the drawings:

10 FIGURE 1 is an oblique view of the counter made according to the invention but with one of the doors in open position.

FIGURE 2 is a section taken on the line II—II of FIGURE 1.

15 FIGURE 3 is a section taken on the line III—III of FIGURE 1.

FIGURE 4 is a section taken on the line IV—IV of FIGURE 1.

20 FIGURE 5 is a section taken on the line V—V of FIGURE 1.

FIGURE 6 is a section taken on the line VI—VI of FIGURE 1.

FIGURE 7 is a section taken on the line VII—VII of FIGURE 1.

25 FIGURE 8 is a section taken on the line VIII—VIII of FIGURE 1.

FIGURE 9 is an oblique view of the forward frame member of the counter.

30 FIGURE 10 is an oblique view of the rearward frame member of the counter.

FIGURE 11 is a section taken on the same plane as line III—III of FIGURE 1 and illustrating a modification.

FIGURE 12 is a section taken on the line XII—XII of FIGURE 1.

35 FIGURE 13 is a section taken on line XIII—XIII of FIGURE 1.

FIGURE 14 is a section taken on line XIV—XIV of FIGURE 1.

40 FIGURE 15 is a section taken on the same plane as line III—III of FIGURE 1 and illustrating a further modification.

FIGURE 16 is a section taken on the line XVI—XVI of FIGURE 5.

With reference now to the drawings, there is shown one specific embodiment of the invention which has been selected for illustrative purposes. However, it will be recognized that this embodiment represents only one assembly of which the parts are capable and the selection of this arrangement for illustrative purposes will be recognized as illustrative only and with no limiting intention.

Turning now to the construction in detail, a first side of the counter, which may be for reference purposes hereinafter denoted as the "forward" side is provided with a frame 1 comprised of end members 2 and 3, a top member 4 and a bottom member 6, which members are permanently and rigidly fastened together in any convenient manner, such as by welding. Said frame 1 also includes an inwardly or rearwardly offset member 7 and a downwardly extending member 8 at one end of frame 1 and their counterparts 7a and 8a at the other end of the frame 1, which parts are also permanently and rigidly affixed to the other frame members in any convenient manner, such as by welding. The end members 2 and 3 are preferably made from hollow, rectangular, metal tubing, although other materials and specific shapes are conceivable within the broader scope of the invention. The top member 4 is an inverted U-shaped member and the bottom member 6 is likewise a U-shaped member similar to the member 4 and opening upwardly toward said member 4. The members 4 and 6 may be made as metal or plastic extrusions, if desired, but they are preferably, and in this embodiment, made by rolling.

In the particular assembly shown in FIGURE 1, where sliding doors are to be used in the frame 1, the upper rail 4 is formed to define a pair of channels 11 and 12. The bottom rail 6, however, has a door guide 13 having channels 14 and 16 therein and positioned oppositely to the channels 11 and 12, respectively. The channels of the guide 13 are generally similar to the channels of the top member or rail 4 excepting that the channels 14 and 16 are shallower than channels of the rail 4 in order to facilitate installation and removal of the panels hereinafter mentioned. In this embodiment a filler 17 is disposed between the webs of the member 6 and guide 13 for spacing purposes. Said filler may be made of any convenient material, such as wood. The door guide 13 can be made of any desired material, such as extruded metal or plastic, but is preferably made of a self-lubricating extruded plastic, such as nylon.

On the opposite side of the counter, which will hereinafter be denoted as the "rearward" side for convenient reference, there is a further frame member 21 which is made in all essentials in the same manner and from the same materials as the frame 1, except that the offset provided by member 7 in frame 1 is not provided in frame 21. The rearward frame 21 has vertical end members 22 and 23 which are preferably identical, respectively, to the front end members 2 and 3. It also has top and bottom horizontal members 24 and 25 which are identical in all respects to the front, top and bottom members 4 and 6 excepting, in the specific form shown, that there is in frame 21 no door guide corresponding to guide 13. The frame 21 also has downward extensions on the end members 22 and 23 comprising feet portions 27 and 28 corresponding to the feet portions 8 and 8a of the front frame member 1. All of the feet portions 8, 8a, 27 and 28 may, if desired, be provided with glides as shown at 71 in FIGURE 5. The parts of rear frame member 21, like those of the front frame member 1, are fastened together in any convenient manner, such as by welding.

The two frame members 1 and 21 are associated with and held rigidly with respect to each other by the side sheets 31 and 32, a top structure 33 and a bottom sheet 34.

The side sheet 31 has its opposite side edges angularly bent to form vertical flanges thereon, of which one is shown at 36 (FIGURE 6), said flanges being fastened to the vertical posts 2 and 22 in any convenient manner, such as by drive rivets, of which one is indicated at 37. The lower edge of said side sheet 31 is also provided with a flange 38 (FIGURE 8). The upper edge of the side sheet 31 is provided with a flange 39 (FIGURE 3) upon which may be supported the top structure 33 as set forth hereinafter.

The side sheet 32 is similar to the side sheet 31 and is fastened to the parts associated therewith in the same manner.

Bottom sheet 34 comprises a planar sheet having stiffening flanges at the sides and ends thereof. The shape of one of the side flanges on sheet 34 is illustrated in FIGURE 8 wherein said flange is reversely bent as shown at 41. The flange at the other side of sheet 34 is similarly shaped as shown at 41a (FIGURE 16). The front and rear end flanges are also downwardly extending and reversely bent, as indicated at 42 (FIGURE 5) and at 42a (FIGURE 14). Said bottom sheet 34 is supported on and by means which are described hereinafter.

In the embodiment shown in the drawings, the top structure 33 comprises a box here assumed to be a wooden box having side walls 45 and a bottom wall 46. Said bottom wall rests at its sides upon the upper flange 39 and its counterpart at the other side of the counter and at its front and rear edges upon the upper side of the upper members 4 and 24 (FIGURES 3 and 4). Said box 46 may be fastened thereto in any convenient manner, such as by screws, of which one is indicated at 47,

extending through the inwardly turned flanges, as the flange 39, on the upper edges of the side sheets 31 and 32.

Bottom filler sheets, of which the front and back ones appear at 48 and 49, are provided, respectively, between the feet of the frame structures 1 and 21. These sheets have the flanges 48a and 49a for supporting the bottom sheet 34. These are preferably welded in place. Side filler sheets, of which one appears at 50 have inwardly turned L-shaped flanges 51 (FIGURE 2) which are received within suitable clips, such as the clip 52 shown in connection with the foot 8 and welded thereto. The bottom filler sheet 50 is slid into place from the top of the assembly prior to the mounting of the end sheets 31 and 32. The fastening of the other end of the bottom filler sheet 50 to the foot 27 and the fastening of a corresponding bottom filler sheet between the feet 8a and 28 is carried out in the same manner as above illustrated with respect to the foot 8.

The front frame is, in the illustrated embodiment, supplied with doors 56 and 57 which are inserted into the respective channels in a known manner, as illustrated in U.S. Patent No. 2,910,740. Thus, the door 56 is disposed in channels 12 and 16 and the door 57 is disposed in the channels 11 and 14, and said doors are sufficiently smaller in vertical dimension than the corresponding distance between the bottoms of said channels that said doors may be readily slipped into position or removed therefrom.

The rearward wall of the counter assembly may, if desired, be closed by a rearward sheet 61 having end flanges, of which one appears at 62 (FIGURE 6). The upper and lower edges of said back sheet 61 are received into corresponding ones of opposed channels of the back horizontal rails 24 and 26 (FIGURES 12 and 14). The upper and lower edges of said back sheet 61 are stiffened by bending over the edges thereof to provide flanges similar to the end flanges, said flanges here being of such width as to enable said sheet to be received as desired into the channels.

It will thus be seen that the entire unit can be shipped in a single package and the general organization is sufficiently indicated by the front and back frames that it is self evident, even without the use of written instructions, how the parts go together that the assembly procedure itself proceeds with only simple tools required.

Many variations in the counter assembly are readily possible. For example, the doors 56 and 57 may be either opaque as indicated in the drawings wherein they are shown as being formed of sheet metal, or they may be made of wood if desired for any reason, such as appearance, or they may be of glass if it is desired to expose the contents of the counter to view. Such doors are provided in this embodiment on the front of the counter, and such doors could be added in the rear if desired by lifting out the back panel 61 and inserting a double U-shaped track in the bottom channel like that in the front lower channel.

Conversely, the front of the cabinet may be closed by removing the double U-track 13 and inserting a panel similar to panel 61, which may be of any desired material. Shelf supports 66 and 67 of any conventional type may be provided in the end panels 31 and 32 and conventional shelving, not shown, utilized in connection therewith.

The box 33 shown in the drawings may, if desired, be replaced by single planar top members, as shown at 64 and 65 in FIGURES 15 and 11, respectively. Such top panels may be made of any convenient material, such as wood or a suitable plastic composition or metal.

Although particular preferred embodiments of the invention have been described above in detail for illustrative purposes, it will be recognized that variations or modifications of such disclosure, which lie within the scope of the appended claims, are fully contemplated.

What is claimed is:

1. In a knock-down type, store counter construction, the combination comprising:
  - an integral, rigid, forward frame having top, bottom, and end members, the end members of said forward frame each having an integral extension extending rearwardly from the lower end thereof, said extensions each having an integral depending, vertical leg thereon at the end thereof for supporting said forward frame;
  - a rearward frame similar to said forward frame, the end members of said rearward frame each having an integral, collinear leg depending therefrom for supporting said rearward frame;
  - a pair of similar side sheets releasably attached to and extending between corresponding end members of said frames whereby to provide a rigid and self-supporting counter structure; and
  - top means at least partially supported on said frames.
2. The construction defined in claim 1, including a bottom sheet filling the area between the bottom members of said frames;
3. In a knock-down type, store counter construction, the combination comprising:
  - an integral, rigid, forward frame comprising top, bottom and end members, the end members of said forward frame each having an integral extension extending rearwardly from the lower end thereof, said extensions each having an integral depending vertical leg thereon at the end thereof for supporting said forward frame;
  - an integral, rigid, rearward frame comprising top, bottom and end members, the end members of said rearward frame each having an integral, collinear leg depending therefrom for supporting said rearward frame, said frames defining rectangular openings of identical size;
  - means defining a pair of downwardly opening channels secured to the top member of each of said frames, said channels being substantially identical; and
  - means defining an upwardly opening channel on the bottom member of each of said frames, said upwardly opening channels being substantially identical and being each substantially equal in width to the combined width of the downwardly opening channels on one of said top members;
  - and means connecting said front and rear frames to each other.
4. A construction according to claim 3, including a

5 door guide removably received within one of said upwardly opening channels, the open upper side of said one of said channels being of sufficient width to allow insertion of said door guide therewithin, said door guide having three substantially parallel, upright flanges, the outer two flanges slidably engaging the legs of said upwardly opening channel.

- 10 5. A construction according to claim 1 including:
  - a front filler sheet extending between said front legs and having a horizontal flange at its upper end;
  - a rear filler sheet extending between said rear legs and having a horizontal flange at its upper end;
  - a bottom sheet extending between said front and rear filler sheets and resting on said horizontal flanges, said bottom sheet having front and rear flanges for engaging the opposing surfaces of said bottom members of said forward and rearward frames;
  - end filler sheets extending between the legs at the respective ends of said frames, said end filler sheets each having a horizontal flange at the upper end thereof and a vertical flange at the inner end of said horizontal flange, said side sheets each having a flange along its lower edge resting on said horizontal flange of one of said end filler sheets, said bottom sheet having vertical flanges at the ends thereof engaging the vertical flanges on said end filler sheets.
- 20 6. The construction according to claim 1 in which the forward and rearward frames each has an inverted L-shaped bottom filler sheet located between the legs thereof, each of said filler sheets having its upper flange forming the L, each extending toward the other frame.
